UNITED STATES PATENT OFFICE.

IRA C. HOFFMAN, OF LA FAYETTE, INDIANA, ASSIGNOR TO THE TRUSTEES OF PURDUE UNIVERSITY, OF LA FAYETTE, INDIANA, A CORPORATION OF INDIANA.

SEED-CORN GRADER.

Application filed March 11, 1927. Serial No. 174,459.

This invention is a novel machine designed for separating and grading seed corn and like grains or seed, according to the size of the grains; and the invention consists in 5 the novel construction and combination of parts as set forth in the claims appended hereto.

The machine is designed to separate the 10 seeds of different size, and collect the grains of like size, by means of a roll and sizing plate and a toothed or barbed belt by which the seeds are moved lengthwise of the roll; said parts being constructed as hereinafter explained.

15 In the accompanying drawings I have illustrated one practical embodiment of the invention, and will describe the same with reference thereto.

In said drawings:

20 Figure 1 is a plan view of the machine; Figure 2 is an end view thereof; Figure 3 is an enlarged detail sectional view on the line 3—3, Fig. 4;

25 Figure 4 is an enlarged top plan view of the seed separating devices, partly broken away;

Figure 5 is a detail view looking to the left on line 5—5, Fig. 3;

30 Figure 6 is a detail view of the supports for plate 4 and guard board 3;

Figure 7 is a transverse sectional view showing a plurality of similar, side by side, grading devices.

The machine is adapted to separate the 35 seeds mechanically into several sizes by passing them along a slot which is regulated in width by a roll 1 of varying diameter and an adjustable plate 5. The plane of the working edge of the plate passes through the center of the axis of the roll and the working edge of the plate is parallel to the center of axis of the roll. On the upper surface of the plate is a movable belt 4 which is preferably serrated or barbed, on the edge next to the roll, to engage and feed the seed. This belt runs on pulleys 14, adjacent the 40 ends of the plate 5, and is preferably of such size and so adjusted that the barbs project beyond the edge of the plate and 45 over the slot as indicated in the drawings.

Above the plate is a guard board 3 which is preferably set at such an angle relative to the plate and the roll that it will with the roll form an approximately V-shaped

trough (see Figs. 3 and 7). The lower edge 55 of the guard board 3 is set approximately flush with the inner edge of the plate 5 beneath it, and substantially covers the belt 4 excepting the barbs 4^a which project into the slot. The guard board may be adjustably 60 secured by bolts 6^a to slotted brackets 6 as shown; or adjustably mounted in any other convenient way.

Above the roll 1 is another guard board 2 which may be supported by any suitable 65 means, as by hangers 2^a. The board 2 and roll 1 form one side of the trough; and said board will prevent any seed passing over the top of the roll. The guards 2 and 3 may be made of wood, metal or other suitable 70 material.

A feed hopper 8 of any suitable construction is mounted on the machine, above and adjacent the larger end of the roll, and is adapted to discharge the seed directly into 75 the V-shaped trough, formed by the roll 1 and guard plates 2 and 3, at the narrowest part of the slot and adjacent the largest end of the roll 1. The hopper 8 preferably has sloping sides which will produce a 80 steady and continuous flow of seed to the grader. The discharge from the hopper is suitably controlled to regulate the flow of seed and prevent clogging the machine.

The roll, plate, belt, and guards are preferably 85 longitudinally inclined so that they slope downwardly from the feed hopper 8 toward the smaller end of the roll; this facilitates the movement of the seed through the trough and along the roll and slot.

The roll 1 preferably has a series of successive sections successively less in diameter. As shown it has three sections *c*, *d* and *e*; the section *e* being the largest and longest; section *d* being shorter and smaller than section *e*; and section *c* being smaller and shorter than section *d*. For grading seed corn the following dimensions of the roll sections have been found useful: Section *e* 2 $\frac{3}{8}$ inches in diameter and 28 inches long. Section *d* 2 $\frac{1}{16}$ inches in diameter and 18 inches long; and section *c* 2 $\frac{1}{4}$ inches in diameter and 8 inches long. These dimensions and the number of the sections may be varied to suit the particular kind of seed to 105 be graded.

Beneath the section *e* is a chute or receiver *E*; beneath section *d* is a like chute *D*; and

below section *c* is a like chute *C*: These chutes are adapted to catch the seed passing through the slot adjacent said sections.

The plate 5 may be made of wood or any suitable materials. It is preferably recessed on the top as shown to receive and guide the belt 4, but the belt may be guided by any suitable means. The plate 5 may be of any desired cross section; and is preferably adjustable toward or from the roll 1, for regulating the size of the slot between it and the roll. As shown the plate is supported by angle bars 5^b adjustably secured to a top member 11 of the main frame by means of bolts 7 and slots 7^a as shown in Figs. 3 and 6.

The belt 4 may be a flexible band, or of any other suitable construction to suit the needs of the seed to be graded. The teeth 4^a of the belt should be of sufficient length to extend over the slot far enough for efficient work but not to interfere with the operation of the roll.

The pulleys 14 will be such as will properly coact with the kind of belt used and may be driven by any suitable means. In the construction shown the pulleys are mounted on parallel shafts 15 adjacent opposite ends of the roll, and shafts 15 are driven in unison by bevel gears 15^a meshing with bevel gears 16^a on a counter shaft 16. One of shafts 15 may be the driving shaft—and is shown as provided with a pulley 15^b by which it can be belted to a suitable driver. The roll 1 may be driven by any suitable means, as shown it has a small pulley 20 on one end driven by a crossed belt 18^a from a pulley 18 on the adjacent shaft 15.

The roller and belt may be operated at any desired speed, and the power supplied by hand, electric or any other suitable means.

The hopper, roll, plate, belt, pulleys, guards, and other parts constitute a single separating unit (Figs. 1-6); and the capacity of the machine may be increased by placing like similar units side by side as indicated in Fig. 7. The single unit, or multiple units, may be mounted upon any suitable framing.

In operation the hopper discharges the seed directly into the V-shaped trough at the narrowest part of the slot. The inner surface of the roll moves upward past the slot. The roll regulates the width of the slot and agitates the seeds, and its direction of rotation prevents the seeds from packing in the bottom of the trough or pinching between the roll and the edge of the plate. The barbs on the edge of the belt carry the seed forward along the slot until they find a section of the slot sufficiently wide for them to pass through. If they are very large they are discharged from the machine by being carried over the lower end. In this manner the smaller seed first pass through the slot, next the medium seed, and then the larger

seed; and the several assorted sizes or grades of seed are directed by the chutes *E*, *D*, *C* into suitable bins or receivers.

I claim:—

1. In a seed grading machine, the combination of a roll of varying diameter, an adjustable plate beside the roll and spaced therefrom to form a slot of varying width between the periphery of the roll and the edge of the plate; means for feeding seed above the slot and adjacent the larger end of the roll; and an endless belt moving lengthwise of the slot and having barbs or fingers projecting over the slot whereby the seed is moved lengthwise of the roll from the narrower to the wider portions of the slot.

2. In a seed grading machine, the combination of a cylindrical roll having a plurality of successive sections successively less in diameter, a plate beside the roll and spaced therefrom to form a slot of varying width between the periphery of the roll and the edge of the plate; means for feeding seed above the slot and adjacent the larger end of the roll; and a movable belt having barbs or fingers projecting over the slot and whereby the seed is moved lengthwise of the roll and slot from the narrower to the wider portions of the slot.

3. In a seed corn grading machine, the combination of a cylindrical roll having a plurality of successive sections successively less in diameter, an adjustable plate beside the roll and spaced therefrom to form a slot of varying width between the periphery of the roll and the edge of the plate; a hopper for feeding seed above the slot and adjacent the larger end of the roll; and an endless belt having a run moving endwise of the slot above the plate and provided with barbs or fingers projecting over the slot, whereby the seed is moved successively lengthwise of the roll from the narrower to the wider portions of the slot.

4. The herein described seed grading machine, comprising a roll of varying diameter; a plate at one side of the roll and adjustable to and from the roll, the space between the roll and adjacent edge of the plate forming a slot varying in width for the passage of the seed; an inclined board above the plate adapted to direct the seed toward the said slot; an endless belt having one run extending lengthwise of board and adjacent the slot and provided with barbs projecting into the slot to carry the seed from the narrower to the wider portions of the slot; a feed hopper adjacent one end of the roll; and discharge chutes beneath the various sections of the slot.

5. The herein described seed corn grading machine, comprising a roll having successive sections successively less in diameter; a plate at one side of the roll and adjustable to and from the roll, the space between the roll and

adjacent edge of the plate forming a slot having successive portions of successively greater width for the passage of the seed; an inclined board above the plate adapted to 5 direct the seed toward the said slot; said inclined board being adjustable; an endless belt having one run extending lengthwise of the roll and adjacent the slot and provided with barbs projecting into the slot to carry the seed from the narrower to the wider portions of the slot; a feed hopper adjacent 10 one end of the roll; and discharge chutes beneath the various sections of the roll.

6. In a seed grading machine, the combina-

tion of a roll, a plate beside the roll and 15 spaced therefrom to form a slot of varying width between the periphery of the roll and the edge of the plate; means for feeding seed above the slot and adjacent the narrower end of the slot; and a belt movable lengthwise of the slot and having barbs or fingers projecting over the slot whereby the seed is moved lengthwise of the slot from the narrower to the wider end thereof.

In testimony that I claim the foregoing 20 as my own, I affix my signature.

IRA C. HOFFMAN.
